SIFTER

Paul J. Barnard, Racine, Wis.

Application November 15, 1937, Serial No. 174,511

1 Claim. (Cl. 209—245)

This invention relates to improvements in sifters.

It is the primary object of the invention to provide sifting apparatus which will pass extremely fine material through an extremely fine screen without clogging the screen.

While the invention is of broad application it can best be understood with reference to specific problems. The device hereinafter to be disclosed as an exemplification of the invention, therefore, will constitute a device for sifting powdered resin through a screen or screens ranging to a fineness of 200 mesh. The process of producing a powdered resin of this high degree of fineness has heretofore involved prohibitive cost. Resin will almost instantly clog a fine screen in the sifting devices heretofore known.

More specifically, the purposes of the present invention involve first, the provision of means whereby the material to be sifted will be deposited in a layer of almost imperceptibly slight thickness on the screen; secondly, the provision of means whereby the portion of the screen through which the material must pass will be not merely vibrated but subjected to sharp impact blows in a direction opposite to that in which the material is intended to pass the screen; thirdly, the provision of means whereby the screen will be automatically cleaned at very short intervals without such abrasion as might destroy so delicate a screen; and, fourthly, passing a gas (preferably air) through the screen in the direction of the material passage therethrough and preferably concurrently with such passage.

Other objects and advantages of the invention will be apparent from the following disclosure.

In the drawings:

Figure 1 is a view in side elevation of a device embodying the invention.

Figure 2 is a view showing in plan a fragment of the screen and the underlying operating mechanism, the screen being broken away to expose such mechanism.

Figure 3 is a view in rear elevation, the separator and collector for air borne material being omitted and portions of the mechanism being broken away to expose the interior construction.

Figure 4 is a detail view taken in section on the line 4—4 of Figure 3.

Figure 5 is a view diagrammatically illustrating a modified embodiment of the invention in axial section through a rotary sifting screen.

Like parts are identified by the same reference characters throughout the several views.

The ground or otherwise finely divided material is supplied through a hopper 15 which preferably includes a baffle 16 over the feeding wheel 17 which is located in the discharge mouth of the hopper and coacts with the wall 18 to deliver minute quantities of the finely divided material from the hopper. For the purposes for which 10 the invention was devised I prefer to cover the feed roll 17 with a lamb's wool surfacing at 20 and to operate it at a speed of approximately 1½ to 2 R. P. M., whereby the material is discharged from the hopper in an almost imperceptible stream upon the sifting screen 21.

The screen 21, for the purposes of the present disclosure, may be assumed to be 160 to 200 mesh. A screen of this mesh is so fine that its reticulations are hardly apparent to the touch. The 20 screen is mounted upon a screen frame 22 pivoted at 23 in the open bearing notches of supports 24.

The entire frame, and the screen 21 therein contained, is set at an angle to the horizontal as clearly appears in Fig. 1. The upper end of the 25 frame is held by tension springs 25 against cams 26 which are mounted on shaft 27 and may conveniently have square peripheral contours. In actual practice I have found it expedient to turn the cams on shaft 27 at a speed of about 400 30 R. P. M., but for other materials and designs it will be understood that changes may be made in such details, the example being illustrative only.

The cams do not merely vibrate the screen but deliver to it a sharp impact in a direction such 35 that the inertia of the powder on the screen will tend to cause the powder to flow through the screen into the collector 28 and thence into the bin 29. Any powder incapable of passing the 40 screen will, of course, be discharged through the reduced end portion 30 of the screen frame 22, or it may be subjected to additional screens in series.

I find that if the powder to be screened is deposited on the screen to any substantial depth a 45 very objectionable clogging of the screen results. The slowly turning feed roll 17 covered with lamb's wool takes care of this phase of the problem by limiting the deposit on the screen to an extremely fine and almost impalpable layer. Clogging would still occur, however, but for an 50 arrangement by which the screen is cleaned at extremely short intervals. The use of the screen cleaning device, together with the means which 55 limits the deposit, keeps the material flowing freely and constantly through the screen.

The screening process preferably involves air (or other gas) flow through the screen with the material. This accelerates the sifting and with some materials the pressure differential may be kept constant at a high value to pass all material with entrained gases. Some materials (such as resin), however, can best be screened if the pressure differential is varied, as by limiting the high pressure differential to a small area of the screen and moving such area about the screen so that the pressure fluctuation will facilitate the cleaning.

For a cleaner in the construction shown in Fig. 1 I prefer to employ a carriage 35 reciprocable transversely beneath the screen on the guide rods 36. Upon this carriage I mount at least one, and preferably two, suction nozzles 38 of sufficient extent longitudinally of the screen frame 22 to comprehend the entire width of the screen 21. By using two nozzles I can cover the screen more often and with a less degree of reciprocation at carriage 35 than would be possible if but one nozzle were used. The two nozzles are connected to vacuum pipes 39 leading to a blower 40 or other means of producing partial vacuum at the nozzle. Flexibility of the pipes or hoses 39 is sufficient to accommodate the reciprocation of the carriage 35. The discharge from the blower preferably leads to a centrifugal vortex separator 41 of conventional design wherein the dust is separated from the air, the dust being delivered through a discharge conduit at 42 into a suitable collector at 43. Since this material has passed the screen it should be of substantially the same fineness as that collected in the container at 29.

A convenient means of operating the various parts is shown in the drawings but will be understood to be not essential to the invention. The motor 45, through suitable chains 46 and 47 and sprockets therefor drives the shaft 27 upon which the cams 26 are mounted. A small pinion at 48 carried by the shaft drives a speed reducing train 49 from which motion is transmitted by chain 50 to the shaft 51 upon which the feed roll 17 is mounted in the discharge throat of the hopper 15.

From pinion 53 on the cam shaft 27 another chain at 54 drives a conventional speed reducing gear set 55 from which motion is delivered through the crank 56 and link 57 to a lever 58 pivoted at 59 and connected to the pin 60 on the reciprocable carriage 35 for the reciprocation of the carriage. The blower 43 may be provided with its own motor at 61.

Each nozzle is narrow and the high pressure area produced thereby is of limited extent. The carriage may be moved at the rate of about fifty reciprocations per minute to shift the elongated pressure areas over the entire screen across the path of material discharge therethrough.

It will, of course, be understood to be well known in this art to pass siftable material from one screen to another, the screens usually increasing in size of opening to produce a series of products of graduated sizes. I contemplate such an arrangement in connection with this invention but have not illustrated it because it is believed that the arrangement would be obvious in view of the foregoing disclosure. The successive screens may be fed and operated and cleaned in exactly the manner already disclosed until

the size of mesh becomes such that the special arrangements herein described are no longer necessary.

It will be noted that the vacuum nozzles 38 are required to move across the lower surface of the screen 21 in very intimate relation thereto. In view of the delicate nature of the screen it is therefore important to protect the screen against abrasive wear.

I have found that I can protect the screen without appreciably affecting the degree of vacuum or the pull exerted by the nozzles on the material tending to clog the screen if I provide on the under surface of the screen two strips of the material ordinarily used in making shims. The strips are shown at 65 and have a thickness which in actual practice need be only one or two thousandths of an inch. They support the screen free of the nozzles and take up the wear, and are readily replaced when necessary. The wear on these smooth surfaces, however, is so slight as to be negligible. The nozzles are preferably fixed to the carriage 35 on the bracket arms 67. There is no occasion, in this device, for mounting them resiliently, as the screen vibration is too rapid for the nozzles to follow. Movement between the nozzles and the screen is also regarded as a desirable means of rapidly varying the pressure differential to which the screen is subject.

For many purposes a rotary device embodying some of the principles of this invention may be employed. I have shown such a device in the accompanying drawings in which a shaft 70 turns in bearings 71 which carry stationary heads 72 closing the ends of a rotatable screen cloth cylinder 75 which constitutes the screen. Material is fed into the device through the hopper spout 76 passing through the head 72'. In the course of rotation of the inclined screen cylinder 75 the material is sifted through the screen in the collector 77 and the coarse grains, incapable of passing the screen, will pass through the opening 78 in the lower screen head 72 on to the discharge table 79.

The sharp impacts desirable for expediting progress of the material through the screen may conveniently be delivered by means of small hammers 80 pivotally carried on one or more shafts at 81 rotatable to cause the hammers to impact the bearings 71 in the desired direction.

The cleansing of the screen may be accomplished by a stationary vacuum nozzle at 83 from which vacuum pipe 84 leads to any suitable source of vacuum such as that already disclosed.

55 I claim:

In a device of the character described, the combination with an inclined screen and means for the vibration thereof, of a feed hopper arranged for the discharge of material on to the screen, a feed roller controlling delivery from said hopper, a nozzle reciprocable across said screen substantially in face contact with the under side thereof, means for reciprocating said nozzle, and means connecting said nozzle with a source of vacuum for the cleansing of said screen, said screen being provided with a wear plate between it and said nozzle comprising a shim sufficiently thin to permit the vacuum of said nozzle to draw air through said screen while relieving said screen of the friction of said nozzle.

PAUL J. BARNARD.
